The ornamental design for a construction machine, as shown and described.

DESCRIPTION

The file of this patent contains at least one drawing executed in color. Copies of this patent with color drawings will be provided by the Office upon request and payment of the necessary fee.

FIG. 1 is a perspective view of a construction machine showing my new design in accordance with a first embodiment;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a perspective view of a construction machine showing my new design in accordance with a second embodiment;

FIG. 8 is a front view thereof;

FIG. 9 is a left side view thereof;

FIG. 10 is a rear view thereof;

FIG. 11 is a right side view thereof; and,

FIG. 12 is a top view thereof.

The broken lines in the drawings illustrate portions of the construction machine that form no part of the claimed design.
